J. O. GARGAN,
SIGNAL LANTERN,
APPLICATION FILED DEC. 28, 1916.
1,291,825. Patented Jan. 21, 1919.

Inventor:

John O. Gargan.

by A. C. Canner, Atty.

UNITED STATES PATENT OFFICE.

JOHN O. GARGAN, OF WEST NEW YORK, NEW JERSEY, ASSIGNOR TO WESTERN ELECTRIC COMPANY, INCORPORATED, OF NEW YORK, N. Y., A CORPORATION OF NEW YORK.

SIGNAL-LANTERN.

1,291,825.

Specification of Letters Patent. Patented Jan. 21, 1919.

Application filed December 28, 1916. Serial No. 139,337.

To all whom it may concern:

Be it known that I, JOHN O. GARGAN, a citizen of the United States, residing at West New York, in the county of Hudson and State of New Jersey, have invented certain new and useful Improvements in Signal-Lanterns, of which the following is a full, clear, concise, and exact description.

This invention relates to signal lanterns, 10 the general object being to provide a new and improved lantern particularly adapted for police signaling purposes in large cities.

One feature of the invention is in a new and improved means for adjustably supporting an incandescent lamp within the lantern, 15 which facilitates locating the source of light at the focal center of the lamp.

Another feature of the invention is in a new and improved means for locking two 20 parts of the lantern securely together.

The invention is described more in detail in connection with the drawings, in which Figure 1 is a top view of the lantern with certain sections broken away in order to 25 show the light-adjusting device and, the means for locking the globe member to the hood; Fig. 2 is a front view of the lantern with parts broken away to show the position of the incandescent lamp and the manner 30 in which the adjusting device is operated; and Figs. 3, 4 and 5 are views showing the details of the adjusting and locking device.

The lantern hood 1, as shown in the drawings, may be made of any suitable material, 35 such as spun sheet metal, according to any suitable design which provides good protection against the weather. To the top of the hood a nipple 2 is fastened which provides a means for suspending the lantern from a pipe containing wires leading to the incandescent lamp socket. The globe member forming the lower part of the lantern comprises the transparent member or shield 3, which may be made of glass in one piece, 40 or of four spheroidal lenses held together and protected by the frame-work of the globe member. In the embodiment of the present invention this frame-work comprises four members 4, 5, 6 and 7 cut from sheet metal of the shape shown, and placed with their concave edges against the transparent member 3 and spaced 90° apart. Intersecting and holding these members together are two heavy wire rings 8 and 9 which encircle 45 the member 3. A metal cylinder 10 sup-

ports the transparent member 3 from the bottom, and is securely fastened to members 4, 5, 6 and 7. Below cylinder 10 and hinged thereto is another cylinder 11 carrying a lens 12, which permits the projection of light in 60 a downward direction. The cylinder 11 is provided with a hinged latch 13 which when released permits it and lens 12 to swing back, allowing easy access to the incandescent lamp within the globe member. The 65 members 4, 5, 6 and 7 are firmly held together at their tops by a flange 14 in which there are notches into which the ends of said members project, as shown in Figs. 1 and 2. When the globe member is brought 70 up under the hood, the metal lugs 15, 16, 17 and 18, which are riveted to the under side of the hood and spaced 90° apart, respectively, enter notches 19, 20, 21 and 22 in the edge of the flange 14. The diameter of the 75 hood at the point just above the lugs is such that the flange 14 will snugly fit therein. The globe member is now locked to the hood by giving it a turn in a counter-clockwise direction until a stop 23 formed in the edge of 80 flange 14 comes in contact with the lug 16. At about the same time, a spring locking device 24, which is riveted to the under side of the flange 14 at the point 25, and has been bent backward by engagement with the lug 85 18, snaps in behind said lug. The globe member is thus securely supported on the lugs 15, 16, 17 and 18, and is prevented from turning either in a clockwise or counter-clockwise direction respectively, by the engagement of spring 24 behind lug 18, and by the engagement of stop 23 with lug 16. To remove the globe member, the spring 24 is pulled downward, thus releasing it from 90 engagement with lug 18, and the whole 95 member turned in a clockwise direction until a stop 26 formed in the edge of flange 14 engages the lug 16. The notches 19, 20, 21 and 22 are then, respectively, directly above the lugs 15, 16, 17 and 18, and by a slight 100 downward movement, the globe member may be disengaged from the hood. Of course, it is desirable that the lugs 15, 16, 17 and 18 and the notches 19, 20, 21 and 22 be spaced closely to 90° from one another in order 105 that any lug may coöperate with any notch.

Within the hood there are two parallel metal bars 27 and 28 which are riveted thereto. Engaging these bars at their center is a vertically adjustable U-shaped mem- 10

ber 29. Each leg of member 29 has a longitudinal slot 30. These slots engage the bolts 31 and 32 held, respectively, in the bars 27 and 28. The member 29 is therefore vertically adjustable with respect to the bars 27 and 28 and may be securely held in any desired position by means of the bolts 31 and 32. Any tendency of the member 29 to rotate around the bolts as an axis, is prevented by transverse shoulders or offsets 33 and 34 in the bars 27 and 28. A standard incandescent lamp socket 35 is fastened to member 29 by means of nipple 36, and may have inserted therein an incandescent lamp 37 of any desired size and shape. In adjusting the lamp to the proper position, the bolts 31 and 32 are loosened, allowing the member 29 to be held only by the friction between it and the bars 27 and 28. Access to the interior of the lantern is had through the bottom by unfastening the latch 13 and allowing the cylinder 11 and lens 12 to swing back on its hinge (not shown). The lamp can then be easily adjusted so that the center of its filament is exactly at the focal center of the lantern. The globe member may then be temporarily removed and the bolts 31 and 32 tightened.

What is claimed is:

- 30 1. A signaling lantern comprising a globe member, a hood member, a source of light within said hood and globe members, means for supporting said source of light from said hood member, and means for attaching said globe member to said hood member comprising a circumferentially notched flange forming part of said globe member,

lugs upon the inside of said hood member adapted to register with the notches in said flange and to engage said flange when the latter is rotated, and a locking spring carried by said flange and adapted to engage one of said lugs.

2. In a signaling lantern, the combination of a globe member, a hood member, means for attaching said globe member to said hood member, a source of light, and means for supporting said source of light from said hood member comprising two bars extending in spaced relation across the hood, a pair of transverse shoulders on one side of each bar, a U-shaped member having a leg fitting between the shoulders of each bar and slidably adjustable across said bar, and means for holding said legs in adjusted positions.

3. In a signaling lantern, the combination of a globe member, a hood member, means for attaching said globe member to said hood member, a source of light, and means for supporting said source of light from said hood member, comprising two spaced bars, each having offset portions therein and extending transversely of and fastened to said hood member, a movable member on which the source of light is mounted, said member fitting against the offset portions of said bars and slidably adjustable across said bars and means for holding said member in any one of a plurality of adjusted positions.

In witness whereof, I hereunto subscribe my name this 27th day of December, A. D. 1916.

JOHN O. GARGAN.
